WATERPROOF WATCH CROWN

Charles B. Greenberg, New York, N. Y., assignor
to Algren Watch Findings Co., Inc., New York,
N. Y.

Application March 17, 1949, Serial No. 81,858

5 Claims. (Cl. 58—90)

1

This invention relates to watch crowns, and more particularly, to waterproof watch crowns suitable for use with watch cases having protecting tubes.

This application for a patent is a continuation in part of my application entitled "Waterproof watch crowns," filed August 17, 1944, and bearing the Serial Number 549,813, now Patent No. 2,479,348, dated August 16, 1949, and contains variations in structure not allowed in the claims therein.

Heretofore, waterproof crowns have been made by inserting a packing and retaining washer therefor into the cup-shaped opening in the crown frame. This structure has resulted in crowns whose fit with their watch case tubes vary greatly in tightness. Some of the crowns grip the tubes so tightly that it is difficult to wind or set the watches and others are so loose that no moisture or dust protection is provided. This variation is due to non-uniformity in the size of the watch case tubes and the bores of the crown packing, and to variations in the physical properties of the packing.

It is therefore an object of this invention to provide a waterproof crown whose fit with a watch case tube can be regulated or adjusted to give any definite desired degree of tightness without changing any of the dimensions of the elements of the crown or of the watch case tube.

Examinations of waterproof crowns of the usual construction have shown that non-uniform gripping pressure between the contacting faces of the crown packing and the watch case tube frequently result in a packing being torn apart, split or excessively worn or abraded and ultimately results in the crown losing its waterproofing characteristic.

It is an object of this invention therefore to provide means causing the crown packing to grip the watch case tube with uniform intensity throughout their entire contacting surfaces.

A shallow, low or small crown has many artistic advantages over a high, big crown and therefore is in far greater demand. However, shallow and small waterproof crowns used with tube-type watch cases do not seal effectively the case against moisture, etc., because of the small area of contact between the crown packing and the watch case tube.

2

Therefore, an object of the invention is to form a large, high crown presenting or giving the appearance of a small shallow crown and so having the artistic advantages of the small crown and the physical advantages of the large crown.

Another object is to form a shallow or small waterproof crown with a relatively great area of sealing contact between the crown packing and the watch case tube.

A small waterproof crown which hugs, or rests close to its case is especially difficult to move or pull out to allow a setting of the watch because of the tight grip between the crown packing and the case and the inability to obtain a secure grip on the crown. The creation of a finger grip by the use of a larger crown or by positioning the crown away from the case results in an unsightly appearing watch and the separated or set off crown presents a problem of increased torque and bending.

Therefore, an object of this invention is to form a waterproof crown which is petite and is positioned hugging the case and also which can be gripped easily and so moved to a setting position.

A further object is to form a waterproof watch crown of a minimum of elements which are easily and simply assembled and to produce a slightly and easily manipulated crown capable of withstanding excessive wear and considerable abuse.

I accomplish these and other objects by forming my crown of a crown frame, a flanged tube, and a resilient annular packing, the crown frame having a crown well and a winding post therein, the flanged tube being force-fitted into the well and engaging the sides thereof substantially for their entire surface area, the flange of the tube being positioned at the outer end of the tube and extending inwardly toward the winding post of the well and the resilient annular packing being longer, when not under pressure, than the depth of the well or tube and being held in position, under pressure, in the well and about its winding post, by the flanged tube whereby the depth positioning of the tube in the well determines the annular diameter of the resilient packing and the intensity of its grip on the watch case tube.

50 A positioning of the tube with its outer end pro-

truding from the well results in an excess of contact of the packing with the watch case tube and provides a finger grip for setting the watch even though the crown is shallow.

For further comprehension of the invention, and of the objects and advantages thereof, reference will be had to the following description, the accompanying drawings and to the appended claims in which the various novel features of the invention are more particularly set forth.

In the accompanying drawings forming a material part of this disclosure;

Fig. 1 is a perspective view of a waterproof watch crown embodying the invention and showing its crown frame, flanged tube, and resilient packing in full line and a watch case tube in dashed line.

Fig. 2 is a sectional view in two parts, shown, on the left side, a crown with its tube flush with its crown frame and with the resilient packing under a maximum pressure, and on the right side, a crown with its tube extending above the crown frame and the resilient packing under less than maximum pressure.

Fig. 3 is a fragmentary view of the crown shown in Fig. 2, right side, positioned on a watch (shown in dashed line).

In the drawings and in the specification, in which like numbers represent similar elements, a waterproof watch crown 10, is shown comprised of a crown frame 11, flanged tube 12 and a resilient packing 13.

The crown frame 11 is cup-shaped, having an opening or well 14 provided with side walls 15, an a bottom 16. A winding post 17, positioned axially in the well, is provided with female threads suitable for engaging the threads of a watch movement stem (not shown).

The resilient packing 13 is positioned in the well about the post and the flanged tube is force fitted into the well with the flange 18 extending inwardly toward the post and exerting pressure on the packing. The sides of the tube which extend substantially to the bottom of the well are in intimate engagement with substantially the total surface area of the walls of the well, so that while the total force of the engagement is great, the unit pressure between the contacting faces is small. This permits the flanged tube to be inserted and gripped by the cup walls with a minimum of distortion, both to the cup walls and the tube. Also, it allows the final end position of the flange to be accurately and definitely established so as to obtain a desired pressure in or on the resilient packing.

The flange 18 extends inwardly covering a substantial part of the end of the resilient packing, but providing an opening large enough to permit positioning of the watch case tube.

More than the normal clearance between the watch case tube and the flange is needed as there is a tendency for a trailing edge 19 of the resilient washer to adhere to the watch case tube when the crown is moved away from the watch in the setting operation and this edge becomes wedged between the watch case tube and the inner edge 20 of the flange. The return of the crown to the watch does not release the caught edge 19. This results in an excessive and non-uniform pressure by the packing and causes abnormal wear and makes winding difficult.

The pressure, created by the flange pushing against the packing, is transmitted longitudinally and laterally throughout the resilient packing and causes the packing to grip the side walls of

the tube, the bottom of the well and the watch case tube (shown in dashed line) which is inserted into the well, when the watch stem is threaded into the crown post. Thus the packing forms a closure about the watch case tube and so shuts and seals off the watch case opening through which the watch stem extends.

During the winding operation of a watch provided with the crown 10, a twisting or torque is developed in the resilient packing as the packing rotates with the crown while gripping the watch case tube which remains stationary. To carry and transmit this torque properly, the packing must grip the watch case tube uniformly throughout their area of contact and also the packing must grip the side walls of the flanged tube uniformly throughout their area of contact, and both areas of contact must extend substantially for the full height and depth of the crown well. Without the uniform pressure and the full areas of contact, there is a tendency for the packing to be twisted and torn. This occurs when one end of the packing grips the watch case tube and the other end grips the flanged tube of the crown. In addition, there is a tendency where there is non-uniform pressure for the packing to wear unevenly and for the crown to lose its waterproofing characteristic. Uniform pressure throughout the packing is obtained by providing substantial encasement of the packing within the tube of the crown and that all the pressure supplied to the packing be in a direction parallel to the axis of the tube.

The total pressure, or the grip of the crown packing about the watch case tube must be sufficient to provide an effective waterproof seal but must not be so large as to prevent the winding and setting of the watch. The ultimate location of the flange of the crown tube, which creates the packing pressure, therefore, becomes highly important. As all batches of resilient packing are not of exactly the same resiliency and the resultant packing therefrom cannot have exactly the same inside and outside diameters and as the specifications of all watch companies for watches of the same size are not the same for their watch tube elements a standard location for the flange cannot be set to give the required pressure and result in a crown having a good waterproof characteristic and also being easily wound and set.

In making the crown 10, the variations in the physical properties of the packing and the dimensional variations in the watch case tubes are considered and the depth to which the flanged tube 12 is inserted in the crown well is appropriately corrected to correspond to the different specifications. Thus, without changing any of the crown frame, flanged tube or resilient packing basic dimensions, a crown is formed which can be adapted to function perfectly with many sizes of watch case tubes.

The crown 21 (left side of Fig. 2) is shown with its flanged tube 22 inserted into the crown well so far that the upper edge 23 of the flange is flush with the top of the crown frame, while in the crown 10 (right hand side of Fig. 2) the outer face 24 of the flange of the tube 12 extends above the crown frame 11.

The setting operation of a watch is made easy by the crown 10 as its extending flange is in close proximity to the watch case, while the crown frame rests slightly away from the case and thereby provides an opening into which a finger nail can be inserted to retract the crown for setting.

It should be noted that the area of contact between the resilient packing and the watch case tube is greater in the crown 18 than in the crown 21 and as a result, the crown 18 will have a better waterproofing characteristic than the crown 21. A crown developed with an extending flanged tube can therefore be made with a good waterproofing characteristic and having its frame of a low height or shallow and so of a slightly and delicate appearance. The extending flanged tube, therefore, provides a finger grip to aid in setting the watch and permits the construction of a shallower, lower and neater appearing crown.

Although I have shown and described my waterproof crown in its main form and what could possibly be termed a variation, many other variations are possible without departing from the spirit and scope of the ideas conveyed in the drawing and description; therefore, I desire to cover all modifications, forms and embodiments of my invention coming within the scope and language of any and all of the claims here following.

Having thus described my invention, what I claim as new and desire to secure by United States Letters Patent is:

1. In a watch crown suitable for use with a tube type watch case, a crown frame having a crown well, a resilient annular packing resting in said well and a tube having an inwardly extending flange, the tube substantially positioned in the well and gripping the major portion of its wall and the flange exerting pressure on the resilient packing, whereby the packing grips and forms a seal when the crown is applied to the tube of a watch case.

2. In a crown as described in claim 1, having its flange extending over only a substantial part of the resilient packing whereby sufficient space is provided between the flange of the crown and the watch case tube to prevent the packing from becoming wedged therebetween.

3. In a watch crown suitable for use with a tube type watch case, a crown frame having a

5 crown well, a resilient annular packing resting partially in said well and a flanged tube having an inwardly extending flange, the tube substantially positioned in the well and gripping a major portion of its wall and extending above the upper edge of the crown frame and its flange exerting pressure on the resilient packing, whereby the packing grips and forms a seal when the crown is applied to the tube of a watch case.

10 4. In a watch crown suitable for use with a tube type watch case, a crown frame having a crown well, a resilient annular packing resting in said well and a tube having an inwardly extending flange, the tube substantially positioned in the well with its lower end spaced from the bottom of the crown well and said tube exerting a light unit pressure against the well wall and the flange of the tube pressing against the resilient packing, whereby the position of the tube in the well can be accurately adjusted to vary the pressure in the resilient packing.

15 5. In a watch crown suitable for use with a tube type watch case, a crown frame, a tube and a resilient annular unitary washer, the crown frame having a crown well, the tube having an inwardly extending flange and the tube being positioned substantially in the well and gripping the major portion of its wall and the washer being positioned between and exerting pressure against the well bottom and the tube flange thereby creating an internal pressure throughout the washer.
